DELETING SYSTEM

Raymond M. Hicks, Plainfield, N. J., and Charles S. Whitney, Brooklyn, N. Y., assignors to The Teleregister Corporation, New York, N. Y., a corporation of Delaware

Application July 29, 1932, Serial No. 625,770
Renewed July 17, 1936

23 Claims. (Cl. 178—4)

This invention relates to improvements in stock deleting systems and mechanisms.

Among the objects of this invention are the provision of a method and system for dividing or segregating all or any desired received information into groups for printing, recording, displaying, storing, retransmitting or other like purposes.

Other objects of this invention are the provision of mechanism for controlling one or more tickers to print the prices of only such stocks as are desired; the provision of mechanism for preventing the printing of the price of any stock beginning with any letter of the alphabet and which may comprise a one, two or three letter designation, one of several different issues of the stock, and preferred stock; the provision of mechanism whereby the prices of all of the stocks relating to motors, oils, or the like, may be printed on the same tape by the same ticker, or by different tickers which may be arranged with respect to each other in any desired manner; and the provision of such mechanism which may be controlled directly from the ticker line and which may be located at a central information station or at a subscriber's office, if desired, or in any other convenient place in case the same information is desired by several subscribers.

Other objects of the invention will appear from the following description taken in connection with the drawings, in which

Figs. 1, 2, 3 and 4 show a wiring diagram of one embodiment of the invention.

The drawings show for the purposes of disclosure of this invention, one preferred embodiment of circuits which may serve as an auxiliary to the standard high speed stock quotation ticker system, and by segregating stocks after identifying them by means of storing and classifying their letter abbreviations, may operate to permit the printing of the corresponding prices on one or more groups of tickers, or to prevent entirely the printing of the stock price.

Ticker equipment

Each ticker to be used with this deleting system is preferably equipped with a printing control magnet of the type now employed in connection with deleting tickers as shown in Letters Patent of the United States No. 1,814,902, granted January 31, 1930 to R. F. Dirkes. This magnet is preferably normally energized to hold a projection on a member operated by its armature interposed between the ticker printing hammer and the ticker type wheel, thus normally permitting the printing of all quotations. When the print-

ing magnet coil is de-energized, the ticker printing hammer will not find the projection and printing will, therefore, not take place.

In the present application, the printing magnet attached to a ticker associated with this deleting system will normally be operated and remain operated, thus permitting the printing of all characters until the time when a stock which is to be deleted is received. Following the reception of the letter abbreviation for the stock which is to be deleted, the deleting mechanism will function and result in deenergizing the printing magnet of the ticker, so that the price of the stock to be deleted will not appear upon the ticker tape.

As before mentioned, more than one ticker may be associated with this deleting mechanism, and different groups of stocks may be printed or deleted from each ticker group.

Equipment units

The deleting ticker system disclosed comprises the following units:

1. A polarized line relay for receiving line signals;
2. A distributor for distributing the line signals of the six unit permutation code used in the ticker transmission system. This distributor may be of any conventional type, although the drawings show a commutator, (face plate), type, equipped with a second or local ring for controlling certain circuit functions;

3. Various combinations and groups of relays to be described; and

4. One or more plug and jack boards for associating the printing magnets of the tickers with the stocks to be deleted.

Detailed description of circuit

The drawings show a ticker circuit L incorporating the line magnets M₁, M₂ and M₃ of standard tickers in series with each other and with the winding of the polarized receiving line relay P of the deleting ticker circuit. A greater number of tickers might be used in series with the line relay, or if desired the ticker line magnets may be on an entirely separate line circuit from that of the line relay of the deleting mechanism.

When the equipment is initially put into operation, all relays will be normal, i. e., unoperated, but the printing magnets on the tickers will be energized from a circuit from ground through a break contact of relay PC—1. It may be assumed that the motor for driving the distributor brushes B₁ and B₂ is in operation, with the friction clutch slipping and the rotatable dis-

tributor brush **B1** resting on the "Start" segment **ST**. If there is no signal transmission taking place over the ticker line the normal battery condition will be held on the line; this will 5 be a potential in a direction to hold the armature of the receiving line relay **P** of the deleting system against its marking contact, designated **M**.

Upon reception of the first character, the polarity of the line wire is first changed so that the 10 armature of the line relay moves to the spacing contact, designated **S**. This closes a circuit from ground on the relay armature, through the **S** contact, and winding of the start magnet **SM**, to battery. The start magnet operates, releasing 15 the distributor brushes which begin a rotation on the face plate. As the brushes pass segments **1**, **2**, **3**, **4**, **5**, and **6** of the distributor ring **a**, the associated solid ring **b** which is connected to the **M** contact of the line relay will be opened or will 20 have ground connected to it, depending upon whether or not the line relay armature is resting on the **M** contact, and this in turn will depend upon the code received. Assume the letter **Y** to be received; this letter in the standard ticker code 25 consists of pulses one, three and five marking, and pulses two and four spacing. Pulse six is invariably spacing for letters and is marking only in the case of figures, or for special characters on the lower case half of the ticker type wheel.

As the distributor brush **B1** is passing segment **1** of the ring **a**, the armature of the line relay being on the **M** contact, ground will be connected through this contact, the solid distributor ring **b**, segment **1** of the ring **a**, a break contact **1** of relay **B**, to the winding of relay **1** of the code storage relay group **CSR** No. 1. This relay locks from battery through its own winding and make contact **a** to ground on the break contact **a** of relay **RL-1**. As the brush passes segment **2** the line relay will be on its **S** contact, so that no 30 circuit will be closed through the brush. When the brush is on segment **3** the line relay will be on its marking contact and a circuit will be closed, similar to that just described, which will operate relay **3** of the code storage relay group 35 No. 1; this relay will lock to the same ground as did relay **1**. Similarly, the brush in passing segment **5** will operate relay **5** of the same group but neither relay **4** nor **6** will operate. After leaving segment **6** the brush will pass over a stop 40 segment, designated **SP**, and again come to rest on segment **ST**, with the return of the line condition to marking polarity indicating the completion 45 of the transmission of the letter **Y**. This letter **Y** has now been stored in the code storage 50 relay group No. 1.

While the first letter was being received and stored as described above, the other brush **B2** was passing over the associated local solid and segmented rings **c** and **d** resulting in the following operations. While the receiving line brush was passing segments **1** and **2**, the local brush was traveling across segments **RLS** of the ring **d** thus connecting ground from the local solid ring **c** over a break contact **a** of relay **C** to the winding of relay **RL-2**; this relay operated, but performed no useful function at that time. While the line brush **B1** was passing segments **3** and **4**, the local brush **B2** was passing over segment **TR2**, of the local ring **d**, thus connecting ground from 60 the local solid ring **c** to this segment but performing no useful function. While the line brush **B1** was passing segments **5** and **6**, the local brush **B2** was passing segment **TR1**, of the local segmented ring **d** thus connecting ground from 65 the local solid ring **c** to this segment, thence 70

through a break contact **a** of relay **B** and a winding of relay **A** to battery, operating relay **A**. The operation of relay **A** closes a circuit from ground through a break contact **b** of relay **C**, make contact **a** of relay **A**, to one end of a winding of relay **B**. The other end of this same winding of relay **B** has ground connected to it from the segment **TR1** of the local distributor ring **d**, over break contact **a** of relay **B**. Relay **B** therefore does not operate at this time. As the line brush leaves segment **6**, the local brush leaves segment **TR1**, thereby removing the ground which had been holding a short circuit on the winding of relay **B**. Relay **B** now operates in series with relay **A** over a circuit as follows: 10 Ground on break contact **b** of relay **C**, make contact **a** of relay **A**, winding of relay **B**, winding of relay **A**, to battery. The operation of relay **B** closes a circuit from ground on its make contact **b**, through the winding of relay **C** to battery, thus 15 operating relay **C**. The operation of relay **C** removes the ground which had operated relay **B** in series with relay **A** as described above; however, the same ground on the contact **b** of relay **B** which has operated relay **C** also passes through 20 the make contact **b** and winding of relay **A** and a winding of relay **B** to battery so that all three 25 relays **A**, **B** and **C** remain operated.

When the line brush **B1** is passing over segments **SP** and **ST**, the local brush **B2** is passing 30 over segment **MARK** of the local segmented ring **d** thus connecting ground to it from the local solid ring **c** and thence through an operated make contact **c** of relay **A**, normal contact **b** of relay **6** of code storage relay group No. 1, to an 35 armature **b** of each of the other relays of the same group. It has been assumed that the letter **Y** was received and stored in this group, so that relays **1**, **3** and **5** will be operated; a path will, 40 therefore, be closed through a make contact **b** of each of these three relays, thence through normal break contacts **1**, **3** and **5** of relay **E**, and normal contacts **a** of relay **C-2**, Fig. 2, to relays **1**, **3** and **5** of the first letter register relay group, 45 Fig. 3, which latter relays will lock over the common locking lead **10**, Figs. 3, 2 and 1, for the group to ground on the break contact **a** of relay **SH**. Because of the large number of contacts required on relay **5** of the letter register relay groups, two 50 relays in parallel **5** and **5a** are used. They function in each letter register relay group, as a single relay. The same ground through the **MARK** segment of the local ring operates relay **SHR**, Fig. 1, 55 which performs no useful function at this time.

When the second letter is received, a similar 60 sequence of events again occurs, with the exception that, since relays **A**, **B** and **C** are now operated, the pulses comprising this second letter will be routed into code storage relay group **CSR** No. 2, instead of into group No. 1 as was the case of the first letter, and relays will be operated in group No. 2 corresponding to the marking pulses 65 of the code for the letter received, in a manner similar to the corresponding reception and storage of the preceding letter in group No. 1 as described.

During the reception and storage of the second letter, the local brush **B2** will again pass over the local rings, and will cause the following operations 70 to take place. When the local brush is passing over segment **RLS**, ground will be connected from the local solid ring, through segment **RLS**, through a make contact **d** of relay **A**, line **11**, through a break contact **c** of relay **BK**, Fig. 2, through a normal contact **b** of relay **C-2**, and 75

through the winding of relay C-1, to battery causing relay C-1 to operate. Ground on a break contact *b* of relay SH, Fig. 1, over line 12, through a make contact *a* on relay C-1 to one end of the winding of relay C-2 will hold a short circuit on the winding of relay C-2 preventing its operation. Ground through the RLS segment of the local ring is also connected at this time through the make contact *a* of relay C to the winding of relay 10 RL-1 which operates and removes the locking ground from all the relays of code storage relay group No. 1, and such of these relays as had been operated during the reception of the preceding letter now release.

15 As the local brush B2 leaves segment RLS, relay C-2 operates in series with relay C-2. The circuit is as follows: From battery, winding of relay C-1, winding of relay C-2, make contact *a* of relay C-1, normal contact *b* of relay SH, to ground. The operation of relay C-2 transfers leads designated 1, 2, 3, 4 and 5 associated with the armatures of relay E from the relays of the first letter register relay group to the corresponding relays of the second letter register relay group, 20 Fig. 3, through break contacts *a* of relay C-4.

25 When the local brush is passing over segment TR2, during this second rotation, ground is connected to this segment from the local solid ring, thence through break contact *a* of relay E, make contact *c* of relay C, and winding of relay D to battery, operating relay D. The operation of relay D closes a circuit from ground, through a break contact *a* of relay F and make contact *a* of relay D to one end of a winding of relay E, but 30 relay E does not operate because it is short-circuited by ground from the local segment TR2. When the brush passes from local segment TR2, the short-circuiting ground on the winding of relay E is removed permitting this relay to operate 35 in series with relay D. The circuit is from ground on break contact *a* of relay F, make contact *a* of relay D, winding of relay E and winding of relay D to battery. The operation of relay E closes a circuit from ground through make contact *b* of relay E to the winding of relay F operating it. The same ground through make contact *c* of relay D, holds relays D and E operated and locked 40 in series.

45 It should be noted that relays D, E and F are 50 mutually interconnected, and are controlled and operated, in the same manner as relays A, B and C. Relays A, B and C are controlled by local segment TR1, while relays D, E and F are controlled in an identical manner by local segment TR2. 55 The only exception occurs during the first rotation of the distributor when all relays are normal; in this case since relays A, B and C are all normal there is no path for the operation of relays D, E and F when the local brush passes for the first 60 time over local segment TR2.

65 During the time when the local brush is passing over segment TR1 on its second rotation, and while the second letter is being received and stored in code storage relay group No. 2, ground 70 is connected from this segment through the make contact *a* of relay B to one end of a winding of relay B, and simultaneously to one end of a winding of relay A. This ground short-circuits the winding of relay A which has been holding this relay locked, and relay A releases, but relay B is held operated by the same ground because it has a direct battery connection on the other end of the same winding. As the brush leaves segment TR1 the holding ground is re- 75 moved from the winding of relay B, which re-

leases. The release of relay B causes the release of relay C, which had been held operated by a ground through the make contact *b* of relay B.

As the local brush passes over the MARK segment of the local ring on the second rotation 5 ground is connected from the local solid ring through the MARK segment, through normal contact *c* of relay A, thence through the break contact *b* of relay 6' to the armatures *b* of the other relays in code storage relay group No. 2. 10 This operation is analogous to that which took place at the same point of the first rotation except that the marking ground was, in the first case, connected to the corresponding armatures of the relays in group No. 1. The marking 15 ground will now have a path, or paths, provided through make contacts *b* of operated relays in group No. 2, thence through operated contacts of relay E and make contacts *a* of relay C-2, Fig. 2, and normal contacts *a* of relay C-4, into 20 the second letter register relay group, Fig. 3, so that relays in this group will be operated as were the relays in the first letter register relay group during the first rotation of the distributor 25 brushes.

When reception of the third letter begins a sequence of operations similar to those just described again occurs, and relay operations take place similar to those which occurred during reception of the first letter; the third letter being stored in code storage relay group No. 1 to which circuits have previously been closed by the release of relay B, as above described. During this third rotation, the passage of the local brush over segment RLS causes the operation of relay RL-2 which releases the relays in code storage relay group No. 2, which had been operated during the second rotation, and also closes a circuit through a make contact *b* of relay D, line 11, break contact *c* of relay BK, Fig. 2, and 30 operated contact *b* of relay C-2, and normal contact *b* of relay C-4 to operate relay C-3. When the local brush leaves segment RLS relay C-4 operates in series with relay C-3 over make contact *a* of relay C-3 and break contact *b* of 35 relay SH, Fig. 1, transferring the leads from the contacts of relay E to the third letter register relay group through the normal contacts *a* of relay C-6.

The above described series of operations now 40 are repeated for each letter received. Five letter register relay groups have been shown on the drawings, so that in the system, as here shown and described, a maximum of five letter characters may be successively received and stored, this 45 number being sufficient to comply with the requirements for identifying individually the majority of stock symbols used on the standard stock ticker system. More letter register relay groups could be provided, if desired, but have 50 not been considered necessary for the purpose of disclosure. The majority of stocks have assigned to them abbreviations consisting of one, two or three letters, with or without the suffix 55 "Pr" denoting "preferred". Some stocks have a suffix .A or .B to distinguish between two issues 60 of the same corporation; for example, Reynolds Tobacco Company has listed on the New York Stock Exchange an A and a B issue which appear on the ticker tape as RJR.A and RJR.B, 65 respectively. This circuit is equipped to receive and store in the fourth and fifth letter register relay groups the combinations .A and .B. The second, third and fourth letter register relay groups are also equipped to receive and store 70 .75

the preferred symbol Pr. It follows, therefore, that this system is arranged to receive and store stock abbreviations of the following general classifications:

5	Classification	Example
Single letter stocks	5	R
Single letter preferred stocks	10	R Pr
Two letter stocks	15	IT
Two letter preferred stocks	20	IT Pr
Three letter stocks	25	AYY
Three letter preferred stocks	30	AYY Pr
Single letter A or B stocks	35	R.A; R.B.
Two letter A or B stocks	40	GM.A; GM.B
Three letter A or B stocks	45	RJR.A; RJR.B

15 In the above tabulation each character shown under the heading "Example" is a separately transmitted character except the preferred designation "Pr" which is transmitted, stored and printed as a single character. In operation, this circuit will receive and store one character in each letter register relay group in order, beginning with the first letter register relay group and proceeding in sequence as long as letter characters are being received.

20 Figures differ from letters in the ticker code by having always associated with them the sixth pulse; i. e., every figure character has a "marking" pulse for the sixth unit of its code. Therefore, when a figure character is received, and stored in one of the code storage relay groups, the relay 6 or 6' will be operated and locked. Then, when the local brush next passes over the segment MARK, ground will be connected from the solid 25 local ring and MARK segment, across contact c of relay A, to the armature b of relay 6 or 6', as previously described, depending upon whether relay A is operated or unoperated at the time, and thence through the operated contact b of 30 relay 6 or 6', a contact 6 of relay E to the winding of relay SH which operates and locks to ground on a break contact of relay SHR. The sixth pulse is usually called the "shift impulse" since it operates the ticker mechanism in such a manner 35 as to shift the printing mechanism from the upper case to the lower case half of the ticker type wheel. The functions performed by the operation of relay SH will be described in a following paragraph.

40 Each letter register relay group, Figs. 3 and 4, contains six relays with contacts wired according to the conventional "fan circuit", providing thirty-two individual outgoing leads, only one of which will be energized through the GI lead to the 45 group, depending upon the combination of operated relays. The feed wire to the "fan circuit" enters the group over lead GI (1) (denoting ground-in), and the outgoing wires of the "fan circuit" terminate on the windings of the letter 50 stock relays. The letter stock relays associated with the first letter relay group are designated first letter stock relays, and the other sets of letter stock relays are designated in an analogous manner. The letter stock relays are provided 55 with two make contacts a and b each; of these contact a is a locking contact associated with a locking lead common to all the relays, the other terminates on a terminal individual to the relay and located on a terminal, or cross-connection, 60 block.

65 Upon the operation of relay RL-1, described above, ground was connected from a break contact b of relay BK through the make contact b of relay RL-1 and break contact c of relay C-2, 70 to lead GI (1) of the first letter register relay

75 group, thence through the fan circuit and to the winding of one of the first letter stock relays corresponding to the operated combination of relays in the first letter register relay group. The first letter stock relay, upon operating, locks over the common locking lead cl to ground through a break contact a of relay LRR, Fig. 2. In a similar manner the operation of relay RL-2 connects ground to lead GI (2) of the second letter register relay group causing the operation of a 10 second letter stock relay.

15 After each letter is received, the succeeding operations of relays RL-1 and RL-2 connect ground to the lead GI of the corresponding letter register relay groups and cause the operation of corresponding letter stock relays.

20 Upon the reception of the first figure character, which, as before mentioned, may occur following a reception of one, two or more letter characters, the relay SH operates as previously described. The operation of this relay opens the locking circuits to the letter register relay groups, releasing all operated relays in these groups; also, by the removal of ground from the common locking circuit prepares for the release of all operated counting relays. The latter relays, however, remain locked to ground on the break contact c of relay PC-1.

25 The letter stock relays and terminal cross-connecting blocks form a translator in which by means of interchangeable cross-connections there may be selected a relay associated with any desired stock. There may be any desired number of these stock relays. Assume, the reception 30 of the abbreviation for stock "A"—in this case the letter A will have been received and stored in the first letter register relay group. The following character will be a figure character having the sixth pulse "marking", which will result 35 in the operation of relay SH. First letter stock relay A will be operated and ground placed on terminal A of the first letter stock relay terminal group. This terminal is cross-connected to one end of the winding of stock relay A, and the other end of the winding of this stock relay is 40 connected to the blank terminal BL of the second letter stock relay terminal group. The armature of stock relay A is cross-connected to the blank terminal of the third letter relay group. In this case no letters are received or stored in 45 the second and third letter relay groups, so that all relays in these two groups will be normal and ground connected to the GI leads of these groups will cause the operation of relays BL of the second and third letter stock relays. This ground is 50 connected to the GI leads GI (2) and GI (3) through the break contacts c of relays C-3 and C-5 respectively, and make contacts of relay EK, which operates in parallel with relay SH.

55 As a result of the above series of operations stock relay A will be operated, and ground will be connected through its make contact to a jack associated with it and correspondingly designated. If one of the series of plugs, shown on Fig. 4, has been inserted in this jack the ground will 60 be extended to the winding of relay PC-1, Fig. 2, which will operate and at its make contact a lock to ground on the break contact a of relay SHR. The operation of relay PC-1 at its contact b opens the circuit to the ticker printing control magnets, PM1 and PM2, which release, thus preventing the printing of the following figure characters. The operation of relay PC-1 at its contact c also removes ground 65 from the locking lead of the counting relays, C-1, 70 75

C-2, etc., permitting them to release. Ground through make contact *c* of relay PC-1 operates relay PC-2, which, in turn, over its operated contact *b* operates relay LRR. The operation of relay LRR at its break contact *a* disconnects ground from the common locking lead for the letter storage relays, which release, removes ground at its make contact *b* from the armatures *a* of relay BK, and at its contact *c* 10 connects ground to the locking lead of the letter register relay groups.

As long as figure characters continue to be transmitted over the ticker system, and to be received by this circuit, relays PC-1, PC-2, LRR, 15 SH and BK remain operated, and the ticker printing control magnets on the associated tickers remain unoperated. As each character is received the distributor brushes make one rotation, and the character is stored in one of the 20 code storage relay groups. As before, relays A, B and C, also relays D, E and F, operate under control of segments of the local distributor ring, so that the successive received characters are stored in alternation in groups No. 1 and No. 2. 25 Because, however, each figure character has its sixth pulse of "marking" polarity, relay 6 or 6' of the group will be operated, and therefore there will be no completed path for ground from the MARK segment of the distributor local ring for 30 the operation of relays in the register relay groups. Neither will the counting relays, C-1, C-2, etc., operate under this condition, since the ground circuit from segment RLS, which normally operates them, is held open at the break 35 contact of relay BK.

When the next letter character is received (which may be after the reception of any number of figure characters) the 6 or 6' relay of the code storage relay group will not operate, since 40 the sixth pulse of a letter character is never of "marking" polarity. Ground through the MARK segment will, therefore, operate relays in the first letter register relay group, simultaneously operating relay SH. The operation of the letter 45 relay permits the release of relays SH, BK, PC-1, PC-2 and LRR. Grounds are thereby restored to the locking circuits of the various relays to permit them to lock when operated, and the printing control magnets on the tickers are re-operated to permit printing of the letter characters. 50 The translator circuit then functions again, as previously described, to translate the new stock abbreviation.

The relay BK, which operates in parallel with 55 relay SH is used for connecting ground to the GI leads of the letter register relay groups to insure translation of "Blanks" in the case of one and two letter stocks. Thus if stock "A" is received, the letter A is received, stored and transferred to the first letter register group. It will not be possible, however, to translate; i. e., to operate the stock relay A until letter storage relays for the second and third letters have been operated. Since no second or third letters will be received in this case, the "blank" relays BL must be operated locally, and this is accomplished by a ground, through the break contact *b* of relay LRR, make contacts *a* in parallel of relay BK, break contacts *c* of relays C-3 and C-5, to the 60 GI leads of the second and third letter register relay groups, thence through the fan circuits of these groups to the corresponding BL relays, it being kept in mind that all relays of these groups will be normal. In the case of stocks of three 70 or more letter characters, the BK relay performs 75

no useful function in translation, since the circuits through its make contacts are opened at the break contacts *c* of the operated counting relays.

Relay PC-2 is used, in connection with the "slow-operate" feature of relay LRR, to delay the removal of locking ground from the relays of the letter storage groups; this is to prevent the premature release of relay PC-1.

Relay PR-1 operates over the Pr lead of register relay group 4 or 5, and will therefore be operated when a three letter or four letter abbreviation followed by "Pr" is received. In translation, its function is similar to the other relays of the letter storage groups.

Relays A and B operate over circuits made through contacts of relays . and relays A and B respectively, and at their contacts complete the circuit for the relay PC-1 over a contact of the stock designation relay such as AM.B; Z.A 20 and XZZ.A, Fig. 3.

Relay SH, in operating, closes a path through its make contacts *b* for operating the relays of the counting chain. This is necessary, following the reception of characters to be deleted, because the operated BK relay holds open the normal operating circuit to the counting relays.

Fig. 2 shows three printing tickers A, B and C, of which A and B are controlled to print the prices of the same stocks. These tickers may be 30 located in different parts of the same office or building or in different subscribers' offices in the same or different buildings. If desired, the subscriber's equipment may include two or more printing tickers such as A and C which are controlled by different PC-1 relays which in turn, as indicated in Fig. 4, are controlled to print the prices of different stocks. If desired, the printing ticker A may be controlled to print the prices of any number or all of the oil stocks and the 40 printing ticker C may be controlled to print the prices of any number or all of the motor stocks. Any desired division of stocks may be made.

While the invention has been described with particularity with reference to the preferred embodiment disclosed, it is obvious that other embodiments may be apparent to those skilled in this art, and it is to be understood that words of description imported from the specification into the claims are not to be considered as words of limitation and that the claims are not to be limited except as necessitated by the prior art.

What we claim as new and desire to secure by Letters Patent of the United States is:

1. The method of classifying information concerning items on a plurality of signal-controlled recorders which normally are operative to legibly record both the designation and characteristics of all items, which consists in selectively controlling said recorders to record the designation 60 of all items and prevent recording of the characteristics concerning an item on any one or more of said plurality of recorders.

2. The method of classifying received information in regard to a plurality of items, which consists in automatically controlling printing devices to omit printing of certain of said information concerning each item as determined jointly by a character or a combination of characters designating each item of information and a characteristic of the remainder of said information.

3. The method of making a record of designation and price information concerning certain of a plurality of items, which consists in controlling a record making device by impulses 75

characteristic of each of a plurality of characters designating the remainder of said items, to print the designation information and omit the printing of the said price information concerning such remainder of the items.

5 4. The method of deleting price information concerning a plurality of items, which consists in controlling a printing mechanism as determined by the characters designating the items, 10 to print the item designation information and omit printing of said price information of said items.

15 5. The method of classifying information concerning items on signal-controlled recorders which consists in controlling each of a plurality of recorders always operative to record the designation of all items in legible form, to selectively omit recording of the remaining characteristics concerning any item.

20 6. In a system of the character described, the combination with a receiving mechanism normally operative to print the designations comprising one or more characters of all items and to print all information concerning said items 25 received, and means controlled by each character of the designation of certain items received and printed, for preventing the printing of the remaining information concerning each of said certain items.

30 7. In a system of the character described, the combination with a printing ticker responsive to a plurality of series of impulses for printing the designation of an item and for printing information concerning said item, of means operable under control of impulses representing the designation of a certain item and which may comprise a plurality of characters for printing said designation of the item and preventing the printing of the remaining information concerning the item designated.

35 8. The combination with a printer controlled by code signals and a shift signal, of means for disabling said printer, and a deleting mechanism responsive to said code signals and including means responsive to a shift signal for operating said disabling means under control of said code signals received.

40 9. The combination with a printer controlled by signals characteristic of letters and numbers and a shift signal, of means for disabling said printer, and a deleting mechanism responsive to letter signals and to a shift signal for operating said disabling means to prevent the printing of numerals.

45 55 10. The combination with a printer responsive to letter and numeral code signals and a shift signal, of means for disabling said printer, and a deleting mechanism including means responsive to one or two letter code signals and a shift signal for rendering said disabling means operative under control of the second mentioned means to prevent the printing of numerals.

60 65 11. The combination with a printer controlled by letter and numeral code signals and a shift signal, of means for disabling said printer, a deleting mechanism responsive to a plurality of letter code signals for rendering said disabling means operative, and means controlled by a shift signal for preventing numeral code signals from controlling said deleting mechanism.

70 65 12. The combination with a printer controlled by letter and numeral code signals and a shift signal, of means for disabling the printer, means under control of letter code signals for rendering said disabling means operative, means under

control of the shift signal for preventing said second mentioned means from acting responsive to numeral codes received, and means under control of letter code signals received subsequently to numeral code signals received for rendering said disabling means ineffective and for rendering said second means responsive to a control by said letter code signals.

5 13. The combination with a printer controlled by letter and numeral code signals, of means for disabling said printer, and a deleting mechanism responsive to letter code signals received and to a special signal included in said numerical code signals for causing said disabling means to function to prevent the printer from printing numerals corresponding to subsequently received numerical codes.

10 14. In a system of the character described, the combination with a receiving mechanism responsive to signals over an incoming line and normally operable to receive designations comprising one or more characters of all items and to post the information concerning said items received, of a deleting mechanism jointly controlled by each character of the designation of selected items and a signal included in the information regarding said items for preventing the mechanism from posting the information concerning each such item during the cycle of operation of the posting mechanism, and means for causing the posting mechanism to post information concerning desired items, said last-named means operating to post the designations of said desired items concurrently with the reception of the signals relating to said items.

15 15. The combination with a plurality of printers controlled to print item designation and price information as to items by signals received over a common line, of mechanism controlled by signals corresponding to the items for controlling said printers to print said item designation information and prevent printing said price information concerning each of said items, and readily changeable cross-connections between said printers and said controlling means whereby the control over each of the printers may be readily varied to cause said price information as to any desired items to be printed on any printer and said price information as to other items to be printed on all of the printers.

50 16. In a system of the character described, the combination with an impulse controlled printing ticker mechanism normally operative to print the designation and prices of all the stocks in reference to which information is received, of a deleting mechanism for controlling the operation of the printing mechanism for preventing the printing of the prices of certain stocks, said deleting mechanism including a receiving distributor, a pair of alternately operable storage relays which are operated by impulses over said receiving distributor, a plurality of stock designation character storing relays controlled by said storage relays, a plurality of letter stock relays controlled by said character storing relays, a circuit closed under control of one or more letter stock relays, and means adapted to be operated over said circuit for disabling the printing mechanism.

55 70 17. In a system of the character described, the combination with a printing ticker mechanism normally operative to print the designation and prices of all the stocks in reference to which information is received, of a deleting mechanism for controlling the operation of the printing

- mechanism for preventing the printing of prices of any desired stocks, said deleting mechanism including a receiving distributor, a pair of alternately operable storage relays which are operated 5 by impulses over said receiving distributor, a plurality of stock designation character storing relays, a plurality of letter stock relays, circuits selectively closed under control of one or more letter stock relays, and means in said circuit 10 for disabling the printing mechanism, each group of storage relays including an additional relay operable as the price information is received for causing said printing controlling means to function.
- 15 18. In a system of the character described, the combination with a printing ticker mechanism normally operative to print the designation and prices of all the stocks in reference to which information is received, of a deleting mechanism 20 for controlling the operation of the printing mechanism for preventing the printing of prices of any desired stock, said deleting mechanism including a receiving distributor, a pair of alternately operable storage relay groups which are operated 25 by impulses over said receiving distributor, a plurality of stock designation character storing relays, a plurality of letter stock relays, a circuit adapted to be made by certain letter stock relays, and means in said circuit for 30 disabling the printing mechanism, each group of storage relays including an additional relay operable as the price is received for causing said printing controlling means to function, said additional relay in each of said storage relay groups 35 operating also to prevent further control of the printing mechanism after the first digit of the price has been received.
19. In a system of the character described, the combination with a printing ticker responsive 40 to impulses over an incoming line and normally operable to print all the information received as to the stock designation and price, of a deleting mechanism also controlled by the impulses received over said line and including 45 mechanism responsive to impulses designating one character or a plurality of characters for preparing a circuit to control the printing mechanism of said printing ticker, and means also included in said mechanism responsive to impulses 50 characteristic of the price for causing said deleting mechanism to function to prevent the printing of the price information.
20. In a system of the character described, the combination with a printing ticker responsive 55 to impulses over an incoming line and normally operable to print all the information received as to designations and prices of stocks, of a deleting mechanism for preventing the printer from printing the prices of any desired stock,
- 60 said deleting mechanism including a receiving distributor, a pair of alternately operable code storage relay groups operated under control of said receiving distributor, a plurality of groups of decoding storage relays, and means under control 65 of the distributor for transferring a set-up contained in the first one of said code storage relay groups operated into the first of said groups of decoding storage relays and operable to successively transfer successive set-ups in said code 70 storage relay groups to said decoding storage groups, said means comprising a counting relay mechanism operable under control of said distributor.
21. In a system of the character described, 75 the combination with a printing ticker respon-
- sive to pulses over an incoming line and normally operable to print all the information received as to the stock designations and prices of stocks, of a deleting mechanism for preventing the printer from printing the prices of any desired stock, said deleting mechanism including a receiving distributor, two groups of code storage relays, switching mechanisms under control of said distributor for alternately connecting said groups of code storage relays to the distributor, 10 a larger plurality of code storage decoding relays, a counting chain, means for connecting operated relays in the code storage groups through said counting chain to operate code storage decoding relay groups in succession, a relay included in each 15 of said groups of code storage relays operated over said distributor by a shift pulse, a shift relay operated from said distributor under control of a relay operated by a shift pulse, means controlled by said shift relay to release said operated counting relays to prevent further counting and to release said decoding relays, a plurality of stock relays corresponding in number 20 to the number of stocks received and operated under control of said decoding relays, and means 25 under control of said stock relays for preventing printing the price of the corresponding stock.
22. In a system of the character described, the combination with a printing ticker responsive to pulses over an incoming line and normally operable to print all the information received as to the designations and prices of stocks, of a deleting mechanism for preventing the printer from printing the prices of any desired stock, said deleting mechanism including a receiving distributor, two 30 groups of code storage relays, switching mechanism under control of said distributor for alternately connecting said groups of code storage relays to the distributor, a plurality of code storage decoding relays, a counting chain, means for connecting operated relays in the code storage groups through said counting chain to operate the code storage decoding relay groups in succession, a relay included in each of said groups of code storage 35 relays operated over said distributor by a shift pulse, a shift relay operated from said distributor under control of a relay operated by a shift pulse, means controlled by said shift relay to release said operated counting relays and to prevent further counting 40 and to release said decoding relays, a plurality of stock relays corresponding in number to the number of stocks received and operated under control of said decoding relays, means 45 under control of said stock relays for preventing printing the price of the corresponding stock.
23. In a system of the character described, the combination with a printing ticker responsive to pulses over an incoming line and normally operable to print all the information received as to the designations and prices of stocks, of a deleting mechanism for preventing the printer from printing the prices of any desired stock, said deleting mechanism including a receiving distributor, two groups of code storage relays, switching mechanism under control of said distributor for alternately connecting said groups of code storage 50 relays to the distributor, a plurality of code storage decoding relays, a counting chain, means for connecting operated relays in the code storage groups through said counting chain to operate the code storage decoding relay groups in succession, a relay 55 under control of said stock relays for preventing printing the price of the corresponding stock, and means also under control of said shift relay for filling blanks in certain of said groups of code storage decoding relays for energizing stock relays corresponding to one or two letter stocks.
24. In a system of the character described, the combination with a printing ticker responsive to pulses over an incoming line and normally operable to print all the information received as to the designations and prices of stocks, of a deleting mechanism for preventing the printer from printing the prices of any desired stock, said deleting mechanism including a receiving distributor, two groups of code storage relays, switching mechanism under control of said distributor for alternately connecting said groups of code storage 60 relays to the distributor, a plurality of code storage decoding relays, a counting chain, means for connecting operated relays in the code storage groups through said counting chain to operate the code storage decoding relay groups in succession, a relay 65 under control of said stock relays for preventing printing the price of the corresponding stock.
25. In a system of the character described, the combination with a printing ticker responsive to pulses over an incoming line and normally operable to print all the information received as to the designations and prices of stocks, of a deleting mechanism for preventing the printer from printing the prices of any desired stock, said deleting mechanism including a receiving distributor, two groups of code storage relays, switching mechanism under control of said distributor for alternately connecting said groups of code storage 70 relays to the distributor, a plurality of code storage decoding relays, a counting chain, means for connecting operated relays in the code storage groups through said counting chain to operate the code storage decoding relay groups in succession, a relay 75 under control of said stock relays for preventing printing the price of the corresponding stock.

lay included in each of said groups of code storage relays operated over said distributor by a shift pulse, a shift relay operated from said distributor under control of a relay operated by a shift pulse, means controlled by said shift relay to release said operated counting relays and to prevent further counting and to release said decoding relays, a plurality of stock relays corresponding in number to the number of stocks received, means under control of said stock relays for preventing printing of the price of the corresponding stock, means also

under control of said shift relay for filling blanks in certain of said groups of code storage decoding relays for energizing stock relays corresponding to one or two letter stocks, and means under the control of the distributor and the relays in said code storage relay groups responsive to shift pulses, for releasing said shift relay and conditioning said mechanism to register and decode stock designation information. 5
